UNITED STATES PATENT OFFICE

KURT BRIEL, OF BROOKLYN, NEW YORK

COMMUTATOR CLEANSER

No Drawing.

Application filed April 21, 1928. Serial No. 271,980.

The object of my invention is the production of a composition of matter adapted for use in the cleansing of commutators on electric motors or armatures of dynamos of all 5 the usual types, which as is well known, must be kept in a cleanly condition and free from metal dust to prevent sparking of the motor, backfiring and short circuiting, together with a marked reduction in the wear of the commutator and the brushes.

In the past it has been the usual practice to effect the said necessary cleansing either by the use of a fine abrasive or by finely polishing or grinding off the exposed surfaces of 15 the brushes and commutator, but these methods have neither of them been completely efficient and have involved the loss of much time and labor.

It is also an important feature that this 20 composition should contain no corrosive or erosive ingredients to prevent injury to the treated parts.

This composition is especially efficient on 25 the type of commutators consisting of a ring of copper segments insulated from one another by non-conducting strips, the segments being connected electrically with the conductors in any of the usual manners.

In addition to being a most efficient cleanser, this composition after application is fire-proof, is very easy to apply, costs very little 30 because of the small quantity needed for each application, and can be manufactured and sold to the consumer at a reasonable figure.

The composition consists of a mixture of 35 oleic acid, yellow paraffin oil, and amyl acetate. In the preparation of the mixture I prefer to use the ingredients in about the following proportions, viz:—

40	Parts
Oleic acid	46
Yellow paraffin oil	44
Amyl acetate	10

Good results may be obtained however, 45 when the proportions are varied within the following limits:—

45	Parts
Oleic acid	46 to 50
Yellow paraffin oil	44 to 48
50 Amyl acetate	8 to 12

In the preparation the paraffin oil is mixed with the amyl acetate, and the oleic acid is warmed until it is clear, after which the ingredients are blended.

In use it has been found advisable to apply 55 a clean piece of dry cloth to the surface running commutator to remove as much as possible of the surface dirt. A cloth is then wet with a few drops of this composition and applied to the commutator to thoroughly 60 cleanse it and leave it with a brilliant glossy surface. In a few days the application should be repeated as the composition is absorbed gradually by the commutator.

I claim:—

A commutator cleansing composition comprising approximately equal parts of oleic acid and paraffin oil with approximately ten per cent of amyl acetate.

In testimony whereof I have hereunto af- 70 fixed my signature.

KURT BRIEL.
